Primary Examiner — Catherine A Tuttle(74) *Attorney, Agent, or Firm* — Perry Hoffman(57) **CLAIM**

The ornamental design for a ball projectile, as shown and described.

DESCRIPTION

FIG. 1 is a front perspective view of the ball projectile showing our new design;

FIG. 2 is a right side elevational view thereof;

FIG. 3 is a left side elevational view thereof;

FIG. 4 is a front view thereof;

FIG. 5 is a rear view thereof;

FIG. 6 is a top view thereof; and,

FIG. 7 is a bottom view thereof.
